UNITED STATES PATENT OFFICE.

WILLIAM RAEURN, OF WATERBURY, CONNECTICUT, ASSIGNOR TO THE HOGE MANUFACTURING COMPANY, OF NEW YORK, N. Y., A CORPORATION OF NEW YORK.

THUMB-TACK AND METHOD OF PRODUCING THE SAME.

1,380,738.

Specification of Letters Patent.

Patented June 7, 1921.

Application filed January 12, 1920. Serial No. 351,031.

To all whom it may concern:

Be it known that I, WILLIAM RAEURN, a citizen of the United States, residing at city of Waterbury, county of New Haven, 5 State of Connecticut, have invented a certain new and useful Improvement in Thumb-Tacks and Methods of Producing the Same, of which the following is a full, clear, and exact description.

10 My invention relates to improvements in thumb tacks and has for its object to provide a new and improved thumb tack formed from a single piece of sheet metal. Heretofore thumb tacks have been formed from a 15 single piece of sheet metal by having a shank cut out from the metal so as to form a pin or point integral therewith, leaving an opening from which the shank was cut out of dimensions corresponding to said 20 shank. The presence of this opening in the thumb tack is very objectionable, since the thumb tacks when once cut out are finished in a rolling barrel and when so treated very often stick together, a prong or shank of 25 one tack entering the opening in another so that not only do the tacks fail to be properly finished but they very often stick together so that it is a very expensive matter to pick them apart and in some cases they 30 will get wedged together so tightly that they have to be scrapped. The object of my invention is to produce a single piece thumb tack in which these difficulties will be avoided, and consists in reducing the opening 35 above referred to so that the difficulties above mentioned are no longer present. My invention therefore consists in a new and improved thumb tack and method of producing the same.

40 The following is a description of my invention, reference being had to the accompanying drawings, in which—

Figure 1 shows in perspective a thumb tack embodying my invention in thumb tacks, looking at it from the under side;

Fig. 2 shows a top plan view of the same;

Fig. 3 shows in perspective a sheet of metal partially formed into thumb tacks embodying my invention and illustrating 50 the method of production;

Figs. 4 and 4^a show the forming dies and punches, and

Figs. 5 and 5^a the punches and dies co-acting therewith.

Figs. 6, 6^a and 6^b show in detail the swaging punch.

Referring more particularly to the drawing, Fig. 1 shows my one-piece thumb tack, the same consisting of a head 1, having projecting from it and integral therewith a point 2, the same constituting a shank which is cut from the body of the metal at all points except adjacent to its base so that its base is integral therewith and bent down to form the prong. After the point is thus formed the metal on each side of the opening from which the point is cut is swaged, as shown at 3, so that that opening is substantially closed. The swaging thins the metal adjacent to the sides of the opening without affecting the thickness of the larger portion of the head or sheet from which it is formed. The thumb tack, therefore, consists of a head having a centrally located point projecting therefrom and integral therewith, the outer metallic surface of the head being substantially continuous, the opening therein being substantially closed by swaging.

These thumb tacks are made upon a single acting pillar press and in making them I preferably use a point-forming punch, a swaging punch, a lettering die, a point straightening die and a blanking die, arranged in the order named. I feed through the press a strip of sheet metal which is first acted upon by the point-forming die 5^a at position *a*, cutting and forming the point shown at 2' in Fig. 3 and leaving an opening 4. The strip is then moved forward to position *b*, with the result that the swaging die 5 hits the metal upon each side of the opening 4, forcing it inward so as to substantially close the opening; as shown at 3'. This swaging punch has an opening 5^b to receive the point of the partially formed tack and has two slightly raised ridges 5² connected by a slightly curved sunken face 5³ for directing the inward flow of the metal. The succeeding punches also have openings 100

5^c, 5^d, 5^e for the point, the opening 5^d in the punch at position *d* being adapted to straighten the point. The strip is then fed forward again to position *c*, whereupon the 5 portion originally treated is subjected to embossing dies 6 for impressing upon the metal destined to constitute the head of the tack any desired lettering or ornamentation. The strip is then fed forward to position *d* so that the point first formed is subjected to straightening dies and is then fed forward to a blanking die and punch 7 at position *e*, which cuts out the head and bends it into a slightly concavo-convex 15 form, after which the thumb tack is subjected to any desired finishing operation, the first step of which is ordinarily the subjecting of it to the polishing action of a rolling barrel.

20 Each action of the pillar press produces one tack ready to be polished, preliminary steps on other tacks being performed simultaneously with the final blanking step.

As will be evident to those skilled in the 25 art, my invention permits of various modi-

fications without departing from the spirit thereof or the scope of the appended claims.

What I claim is:

1. In a sheet metal tack, the combination 30 of a head, a centrally located prong integral therewith and projecting therefrom, said head having a radial division extending to the base of said prong and of lesser width than the width of said prong, the portions 35 of said head adjacent to said division being thinner than the larger portion of said head.

2. The improvement in the process of making a single-piece thumb tack which consists in cutting from a sheet of metal a 40 shank, having its base integrally connected to the sheet and leaving a corresponding opening in the sheet and then swaging the metal of said sheet locally adjacent to said opening so as to reduce said opening and 45 thin the metal adjacent thereto without affecting the thickness of the larger portion of said sheet.

WILLIAM RAEURN.
